H. GARRETT

RADIO FIRE ALARM SYSTEM

Original Filed Oct. 14, 1925

Patented May 17, 1927.

1,629,337

UNITED STATES PATENT OFFICE.

HENRY GARRETT, OF DALLAS, TEXAS.

RADIO FIRE-ALARM SYSTEM.

Application filed October 14, 1925, Serial No. 62,482. Renewed March 28, 1927.

This invention relates to fire alarm systems and has special reference to broadcasting fire alarms to properly prepared vehicles such as motor cars, fire apparatus and 5 the like.

More particularly the invention relates to apparatus which, upon the operation of the usual fire alarm, will signal through radio apparatus to any car or motive apparatus 10 equipped with a receiving set properly tuned for the reception of such signals.

It is well understood that fire alarm signals are transmitted from alarm boxes to the various stations where gongs or other 15 signals are located, local alarm circuits connected to so called "repeaters."

The principal object of the present invention is to provide a novel means for broadcasting the signals received in such stations 20 so that they may be transmitted, without wires, to any receiving stations whether they be located on a moving vehicle such as an automobile or in a stationary position.

With the above and other objects in view 25 as will be hereinafter apparent, the invention consists in general of certain novel details of construction and combinations of parts hereinafter fully described, illustrated in the accompanying drawings and specifically claimed.

In the accompanying drawing the figure 30 is a wiring diagram disclosing the invention.

As here shown the wires 10 lead in from the fire boxes to the magnet 11 of a gong 35 12 having a hammer 13 forming the armature of the magnet and provided with an arm 14 constituting a circuit closer moving under the influence of the magnet into and out of contact with a fixed contact 15. The 40 pivot of the hammer is connected by a wire 16 with a battery 17, the other terminal of which is connected by a wire 18 with a relay magnet 19. From the contact 15 a wire 20 also leads to said magnet 19 so that opening and closing this circuit actuates the relay controlled by said magnet. Also a key 45 21 is bridged across the wires 16 and 20 so that the circuit may be controlled manually and independent of the magnet 11.

The wires of the local alarm circuit to the repeaters are shown at 22 and in this circuit is included a relay magnet 23 controlling an armature 24 which normally engages a fixed contact 25 connected by a wire 50 26 with a relay magnet 27. This magnet is connected by a wire 28 with one terminal

of a battery 29 the other terminal of which is connected by a wire 30 with the armature 24. A key 31 is bridged across wires 26 and 30.

The magnet 27 controls an armature 32 normally out of engagement with a fixed contact 33 connected by a wire 34 with one of the brushes of an alternating current motor 35 having its other brush connected by 60 a wire 36 with one side of the A. C. circuit. The base of this armature connects with the other side of A. C. circuit through wire 38.

This motor 35 drives a governor 39 of the type used in phonographs as a brake 70 and the governor, upon reaching a predetermined speed, engages and closes a circuit closer 40 one element of which is connected by a wire 41 to a battery 42, the battery having its other terminal connected to a 75 relay magnet 43 by a wire 44. From the magnet 43 a wire 45 leads to the remaining element of the circuit closer 40.

The magnet 43 controls an armature 46 which is normally out of contact with a fixed 80 contact 47 connected by a wire 48 with one of the wires 37. The armature 46 is connected by a wire 49 with one brush of an alternating current motor 50 having its other brush connected by a wire 51 with 85 the remaining wire 37. This motor drives a high tension generator 52 having one of its brushes connected by a wire 53 with one terminal of a radio choke coil 64. The other brush of this generator is connected by a 90 wire 55 with the plate of a three element vacuum tube 56. The wires 37 are also connected to a step down transformer 57 which feeds the filaments of the tube 56 and a tube 58 through wires 59 one of which is connected to the second brush of the generator 52 by a branch wire 60. A branch wire 61 connects the plate of tube 58 to wire 55. Both grids are connected by a wire 62. A tuning inductance 63 has the middle point of one winding connected by a wire 64 with a grid leak 65 and one end of this winding is connected to one of the wires 59 while the other end is connected by a wire 65 to the armature 66 of the magnet 19. A variable 100 condenser 67 is bridged across the terminals of this winding. The other winding of the tuning inductance has one end grounded at 68 while its other end is connected by a wire 69 through a chopper 70 to an aerial 105 71. This chopper is driven by a motor 72 having one brush connected to the wire 34

and its other brush connected to one of the wires 37. A fixed contact 73 is engageable by the armature 66 and is connected by a wire 74 with the wire 55.

• The operation is as follows:—

When an alarm comes in the relay of the repeater circuit closes a circuit through battery 29 which operates relay magnet 27 to close a power circuit through the motors 10 35 and 72. When the motor 35 reaches proper speed a circuit is closed through the battery 42 which acts to close the power circuit through the motor 50 thus driving generator 52. Also each breaking and closing 15 of the circuit through wires 18 actuates the relay 19 and thus causes signals to be broadcast from the aerial in accordance with the alarm received.

Having thus described the invention, what 20 is claimed as new, is:

1. In a fire alarm system an alarm receiving apparatus, a high tension generator, radio transmitting apparatus connected to and fed by said generator and 25 including an antenna circuit, means governed by the alarm receiving apparatus for interrupting the antenna circuit, a motor for driving the generator, a normally open local circuit including a relay, a power circuit 30 connected to said motor and closed by said relay, a second local circuit including a relay, and a circuit including a motor and controlled by the last relay, said last circuit controlling through the action of its 35 motor the normally open local circuit.

2. In a fire alarm system, an alarm receiving apparatus, a high tension generator, radio transmitting apparatus connected to and fed by said generator and including an

antenna circuit, means governed by the 40 alarm receiving apparatus for interrupting the antenna circuit, a motor for driving the generator, a first normally open local circuit including a relay, a power circuit connected to said motor and closed by said relay, a second local circuit including a relay, and a circuit including a motor and controlled by the last relay, said last circuit controlling through the action of its motor the first relay circuit, said last motor actuating a governor for closing the first normally 45 open local circuit.

3. In a fire alarm system, an alarm receiving apparatus, a high tension generator, radio transmitting apparatus connected to 50 and fed by said generator and including an antenna circuit, means governed by the alarm receiving apparatus for controlling the antenna circuit, a motor for driving the generator, a first normally open local circuit including a relay, a power circuit connected to said motor and closed by said relay, a second local circuit including a relay, a circuit including a motor and controlled by the last relay, said last circuit 55 controlling through the action of its motor the first normally open relay circuit, said last motor actuating a governor for closing the first normally open relay circuit, said antenna circuit having a chopper interposed 60 therein, a motor driving said chopper, and means controlled by the second local circuit for closing a circuit through the last mentioned motor.

In testimony whereof I affix my signature. 75

HENRY GARRETT.
